UNITED STATES PATENT OFFICE.

ANTOINE FRANCE, OF LIEGE, BELGIUM.

WET SORTING APPARATUS.

Application filed April 10, 1920. Serial No. 372,932.

To all whom it may concern:

Be it known that I, ANTOINE FRANCE, a subject of the King of the Belgians, residing at Liege, Belgium, 353 Rue St. Gilles, have invented certain Improvements in Wet Sorting Apparatus, of which the following is a specification.

The present invention relates to improvements in or modifications of wet sorting apparatus of the kind described in specification of United States Letters Patent Ser. No. 144,796/17, wherein the classification of the minerals, according to specific gravity is obtained by firstly subjecting the minerals to be treated to the influence of a conveying stream of water in a sloping launder or trough and is completed under the action of ascending or upwardly directed streams of water in flooded sorting pockets communicating with the trough through slots in the bottom of same. In the apparatus described in the aforesaid specification, each flooded sorting pocket is provided with a perforated false bottom or screen sloping downwards to means, such as oscillating flaps, adapted to control the discharge of the materials accumulated in the pocket.

The present invention consists in the provision of a sliding wall adapted to permit of the dimensions of the separating pocket being modified, and in the provision of means permitting of a continuous or intermittent discharge of the accumulated material.

In the accompanying drawings, which are somewhat diagrammatic:—

Figures 1 to 4 are lateral sectional elevations illustrating pockets provided with similar means for varying the size of the pockets but different means for controlling the discharge.

Figure 5 is a lateral sectional elevation of a pocket in which the devices for varying the size and for controlling the discharge are duplicated.

Figure 6 is an end elevation corresponding to any of the lateral elevations illustrated by Figs. 1-5.

In the drawings some of the parts bear similar reference numerals to those indicating corresponding parts in the drawings accompanying the parent specification to which reference is made above, the said parts being the trough or conduit 21, the pocket 22, the perforated sloping screen 27, the discharge valve 2—with its operating lever 5 and chain 9—and the water inlet 23.

In the embodiment shown in Figure 1, the size of the pocket 22 is regulated by a sliding plate 44 which is conveniently adjusted by means of a screwed rod 40 passing through a threaded nut in a bracket 41 and provided with a hand wheel 42, although the hand-wheel may be replaced by a nut provided on the outer end portion of the screwed rod and suitably arranged to bear against the bracket 41 when rotated in one direction or the other, the said bracket 41 being secured on the outside to the corresponding wall of the pocket 22. The discharge is controlled by a perforated oscillatory sector-shaped flap 2 as in the above mentioned parent specification.

The operation is as follows:

The flap 2 when closed serves to obtain the accumulation in the pocket 22 of higher specific gravity minerals which the conveying stream in the launder 21 has not been able, owing to the said gravity, to carry further along the launder over the slot in the bottom of the latter and to prevent from settling in the aforesaid pocket, which is thus maintained by the flap 2 full of a product which is not completely clean and of which the classification is completed in the pocket 22 under the influence of an upward stream supplied at 23 and passing through the small holes in the flap 2 and the screen 27.

The flap 2 is controlled by means of an arm 5 which may be operated mechanically, for instance by connecting same as shown at 9 to any suitably driven part, or which may be provided with a weight (not shown) adjusted to allow the movement of the flap 2 only when a sufficient quantity of material has accumulated in the pocket 22 to counter-balance by the action of its weight on the upper face of the flap the action of the said weight on the arm 5. Thus, periodically at intervals calculated to allow the classification of the products filling the pocket 22 to be completed sufficiently, an oscillatory movement is imparted to the flap 2 whereby a discharge opening is formed between the wall 44 and the adjacent edge of the flap to allow the passage of the quantity of dense products to be evacuated each time. It will be readily understood that by increasing or reducing in the manner described above the distance between the sliding wall 44 and the adjacent edge of the flap 2, it will be possible to vary accordingly the size of the aforesaid discharge opening, and also the

size of the pocket 22. Thus by altering the position of the wall 44, the discharge opening may be adjusted while keeping invariable the amplitude of the periodical opening movement of the flap 2. Now, it is important in order to obtain perfectly sorted and clean discharged products that the pocket should as much as possible be kept full of material, and to this end the sliding wall 44 allows to adjust for each category treated at any given time, the distance between the wall and the adjacent edge of the flap 2 so as just to prevent the passage the smaller-sized particles of the said category only during the periods during which the flap is in the closed position while being just sufficient when the flap takes the open position at the end of each of such periods to allow the passage of the larger-sized particles of that category only. If no sliding wall such as 44 was provided, it would be necessary for the aforesaid distance to be such as to prevent when the flap is in the closed position the passage of the smallest-sized grains of the smaller of all categories it is desired to treat in the same apparatus, and to allow when the flap is opened the passage of the largest-sized grains of the larger of the said categories. The distance referred to for the two positions of the flap 2 having thus to be adapted to the two extreme conditions stated instead of being adjustable by means of the sliding wall 44 according to the category treated at any given time, an exaggerated amplitude of the movement of the flap would be required, which would cause a downward movement of the mass of minerals in the pocket 22 which would seriously disturb and hinder the classification therein. It will therefore be clearly apparent that among several other advantages, the present improvement allows the treatment of various categories in the same apparatus and at the same time to obtain, whatever the category treated at a given time may be ideal conditions of evacuation without the serious drawback of having to give to the movement of the flap an exaggerated amplitude. Figs. 2 to 5 show modifications wherein the flap illustrated by Fig. 1 is replaced by equivalent means which are suitably operated to discharge when required the material classified in the sorting pocket, the sliding wall 44 acting in conjunction with the said means to allow the adjustment of the size of the pocket and of the discharge

opening in a manner similar to that described above in connection with the arrangement shown by Fig. 1.

In Figure 2 a horizontal sliding valve 2 is shown as a means for controlling the discharge.

In Fig. 3 the sliding valve 2 is inclined.

In Figure 4 a rotary valve 2 is shown said valve being adapted to rotate continuously so as to secure a continuous discharge.

In Figure 5 the two inclined screens 27 are in the form of sliding plates and a duplex valve 2 is shown, both parts of the valve 2 oscillating.

I claim:-

1. In improved wet sorting apparatus for coal and other minerals, a sloping trough for the classification of the minerals according to specific gravity under the influence of a conveying stream, flooded sorting pockets for completing the classification under the action of ascending water stream, depending from and communicating with said trough, in combination with movable perforated members for controlling the discharge of the sorted products of high specific gravity, arranged in the base of said pockets, and means within such pockets for adjusting the horizontal cross section thereof and the size of their discharge openings, adapted to cooperate with aforesaid movable perforated members for controlling the discharge, substantially as and for the purpose described.

2. Improved wet sorting apparatus for coal and other minerals according to claim 1, having means for adjusting the horizontal cross section and the size of the discharge opening of the pockets consisting of a sliding vertical wall or plate movable in a horizontal direction and worked by means of a screw, substantially as described.

3. Improved wet sorting apparatus for coal and other minerals according to claim 1, having means for adjusting the horizontal cross section and the size of the discharge opening of the pockets consisting of a sliding inclined wall or plate movable in a horizontal direction and worked by means of a screw, substantially as described.

In testimony thereof I signed hereunto my name in the presence of two subscribing witnesses.

ANTOINE FRANCE.
